US0D1073013S

(12) **United States Design Patent** (10) **Patent No.:** **US D1,073,013 S**
(45) **Date of Patent:** **** Apr. 29, 2025**

(54) **WATER FILTER**

(71) Applicant: **Quanzhou Ouweipai Sanitary Ware Co., Ltd.**, Quanzhou (CN)
(72) Inventor: **Senxin Zhao**, Quanzhou (CN)
(73) Assignee: **Quanzhou Ouweipai Sanitary Ware Co., Ltd.**, Quanzhou (CN)

(**) Term: **15 Years**

(21) Appl. No.: **29/982,996**

(22) Filed: **Jan. 8, 2025**

(30) **Foreign Application Priority Data**

Dec. 2, 2024 (CN) 202430763423.3

(51) **LOC (15) Cl.** **23-01**

(52) **U.S. Cl.**

USPC **D23/209**

(57) **CLAIM**

The ornamental design for a water filter, as shown and described.

DESCRIPTION

FIG. 1 is a top perspective view of a water filter, showing my new design;

FIG. 2 is a front perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the water filter, which form no part of the claimed design.

1 Claim, 9 Drawing Sheets
